UNITED STATES PATENT OFFICE.

ERNST HORN, OF BERLIN, GERMANY, ASSIGNOR TO SIEMENS & HALSKE AKTIEN-
GESELLSCHAFT, OF WERNERWERK, SIEMENSSTADT BEI BERLIN, GERMANY.

TELEPHONE SYSTEM.

Application filed September 7, 1923, Serial No. 661,445, and in Germany September 9, 1922.

In telephone systems it is often required that in some cases a selecting device be operated several times by number impulses from one point, while for setting up other calls the selecting device remains at rest for the duration of the call after it has been operated once. Such selecting devices are for instance the auxiliary digit switches, or switching repeaters which in telephone areas having main and sub-exchanges bring about the switching over of the connection to connecting devices of the local exchange when the transmission of particular trains of impulses indicates that a local connection is to be set up. The auxiliary digit switches can, however, also be used for effecting certain circuit changes, e. g. determining the value of a call and can connect up the meter operating device for zone metering only when particular trains of impulses are transmitted.

In known circuit arrangements it is necessary for auxiliary relays to be energized in the positions in which the switch stops, these relays bringing the driving magnet of the selecting device under the control of the calling station for further trains of impulses also. The number of these relays considerably increases the capital cost of such a system.

Now the object of the present invention is to avoid increasing the capital cost of such a system due to auxiliary and switching relays, thereby increasing the commercial efficiency of the system. This is achieved since after the selecting devices have been set on particular contacts, they are automatically moved into a definite position from which they are moved onwards again under the control of further trains of impulses transmitted from the calling station.

The drawings show one method of carrying out the invention.

In Figs. 1 to 4 are shown the circuits concerned in setting up different connections.

Fig. 5 shows the relative position of the main and sub-exchanges, illustrating in solid lines the route over which connections are established, and in interrupted lines the actual distance between the exchanges which determine the rate of charge which will be made between the various exchanges.

Figs. 6 and 7 show the meter control switches MS_2 and the distributing frame V_{1e} as they are connected up for exchanges UA_1 55 and UA_2 .

Fig. 8 shows, diagrammatically, the connecting devices of a main exchange HA and a sub-exchange UA_1 .

A connection between the subscriber T_{n_1} of 60 the sub-exchange UA_1 and the subscriber T_{n_5} of the sub-exchange UAX will first be explained, both these subscribers being in the same traffic zone.

When the subscriber T_{n_1} originates a call, 65 the relay R_1 of the preselector I.VW₁ operates in known manner and causes this preselector to set itself on a free II.VW₁. When this has been done, the following circuit is established: earth, battery, contact 1_{r_1} , windings I and II of relay T_1 , wiper 2, contacts 3, 4_{t_1}, relay R_2 , earth. The relay T_1 in known manner stops the preselector, disconnects the calling relay R_1 at the contacts 5 and 6_{t_1} and connects through the speaking leads a , b at 70 the contacts 7 and 8_{t_1}. At the second preselector II.VW the operated relay R_2 at contact 9_{r_2} closes the circuit of the driving magnet D_1 and at contact 10_{r_2} prepares the energizing circuit for the test relay T_2 . The 75 circuit of the driving magnet extends as follows: earth, battery, contacts 9_{r_2} , 11_w, magnet D_1 , contacts 12_{d_1}, 13_{t_2}, earth. The following circuit is established when the second preselector II.VW₁ finds a free repeater Ue 80 and associated therewith a free trunk line VL_1 leading to the main exchange HA: earth, battery, contact 10_{r_2} , windings I and II of relay T_2 , contact 14_w, wiper 15, contact 16, lead 17, contact 18_s, winding I of relay C_1 , contact 19_{v_1}, earth. The relays T_2 and C_1 operate. The relay T_2 at contact 13_{t_2} opens the circuit of the driving magnet D_1 , at contact 15_{t_2} short circuits its high resistance winding I and switches through the testing and blocking lead from the first preselector I.VW₁ to the repeater Ue and simultaneously disconnects the relay R_2 at contact 4_{t_2}.

Furthermore at the contacts 20 and 21_{t_2} the speaking leads are switched through to the feeding bridge at the repeater Ue , which comprises the relays A_1 and B_1 whereupon both these relays operate. 100

At the repeater, the relay C_1 closes its con-

tact 22 and thus prepares a holding circuit over its winding II. Furthermore at contact 23_{c1} the impulse contact 25_{a1} of relay A₁ is connected to the lead 24 of the trunk line VL₁.
 5 The operated relay A₁ opens the contact 25_{a1}, over which are given the impulses for setting the numerical switches, at contact 26_{a1} short circuits the relay V₂ while at the same time by opening contact 27_{a1} removing the short circuit from the winding II of relay C₁ and also opens the impulse contact 28_{a1} for the magnet D₂ of the auxiliary digit switch MS₁. Among other circuit changes the relay B₁ opens its contact 29_{b1}, thereby removing the short circuit round the winding I of relay V₁. The latter operates, opens its contact 19, 30 and 33_{v1} and closes its contacts 31 and 32_{v1}. The closure of the contact 32_{v1} causes the rotary magnet D₂ of the auxiliary switch MS₁ to be connected up: earth, contacts 32_{v1}, 34_{v2}, wiper 35, contact 36, magnet D_{2(ms1)} battery, earth. The wiper 35 is moved on to the second contact 37 and thereby the following circuit is closed: earth, contacts 32_{v1}, 34_{v2}, wiper 35, contact 37, lead 38, winding 39 of the repeater, contact 40_{v2}, lead 41 of the trunk line VL₁, contacts 42_{c2}, 43_{hr}, relay V₃, winding I, contact 44 of the auxiliary switch MS₂, wiper 45, resistance 46', battery, earth. The relay V₃ operates, opens its contact 46_{v3}, and closes its contacts 47_{v3}, 48_{v3}, 49_{v3}, and 50_{v3}. At contact 48_{v3}, the rotary magnet D_{3(ms2)} of the auxiliary digit switch MS₂ is connected to the impulse contact 51 of a relay A₂, while at the contact 49_{v3}, the first group selector of the main exchange is taken into use over the following circuit: earth, contact 49_{v3}, relay C₂, resistance 52, contact 53_{s1}, lead 54, off normal contact 55_{s1} of the first group selector I.GW₁, winding I of relay B₃, winding I of relay C₃, battery, earth. The relays C₂ (Fig. 2) as well as B₃ and C₃ (Fig. 3) operate. The relay C₂ closes the contact 56_{c2} located in parallel with 49_{v3}, opens the contact 42_{c2} and closes the contacts 57 and 58_{c2}. At contact 57_{c2} the lead 41 is connected with the lead 59 to the first group selector I.GW₁, while at contact 58_{c2} the relay V₃ is maintained energized, after its original energizing circuit is opened at contact 42_{c2}. The holding circuit extends as follows: earth, battery, resistance 46', wiper 45, contact 44, winding I of relay V₃, lead 60, normal contact 61, wiper 62, contact 58_{c2}, earth. At the first group selector I.GW₁, the relay C₃ by closing the contact 63_{c3} prepares a holding circuit over both its windings I and II, which becomes operative as soon as the contact 55_{s1} is opened at the first step of the group selector. The relay B₃ at its contacts 64 and 65_{b3} connects the relay A₃ to the lead 66 and connects the winding II of relay B₃ to the lead 59. The impulses of the first train transmitted by the

calling subscriber, besides operating the first group selector I.GW₁ located at the main exchange, also operate the auxiliary digit switch MS₂ located in front of this group selector and the auxiliary digit switch MS₁ in the sub-exchange. It will be assumed that for this connection only a single payment has to be made, since the sub-exchange UAX lies in the same traffic zone as the sub-exchange UAI. If for instance the first train of impulses comprises three impulses, then all the three numerical switches (I.GW₁, MS₁, MS₂) are moved on three steps. The impulses are sent in known manner by interrupting the loop at the calling subscriber's station, so that the relays A₁ and B₁ release at each impulse and the relay A₁ closes its impulse contacts 25_{a1} and 28_{a1}. The circuits for operating the different apparatus extend as follows:—
 1. For the auxiliary digit switch MS₁ in the sub-exchange: earth, contacts 32_{v1}, 67_t, 28_{a1}, 36, magnet D₂, battery, earth.
 2. For the impulse receiving relays A₂ (Fig. 2) and A₃ (Fig. 3) in the main exchange: earth, contacts 25_{a1}, (Fig. 1) 23_{c1}, lead 24, thence over relay A₂, contact 50_{v3}, resistance 68, battery, earth, and also thence over contact 69_{t3}, lead 66, contact 64_{b3}, relay A₃ battery, earth.
 The relay A₃ in known manner brings about the setting of I.GW₁ on the third level. The relay A₂ (Fig. 2) closes the circuit for the driving magnet D_{3(ms2)} as follows, earth, contact 51_{a2}, winding II of relay V₃, contact 48_{v3}, magnet D_{3(ms2)} battery, earth. Hence at the end of the train of impulses the wipers 45 and 62 of the auxiliary digit switch MS₂ stand on the contacts 70 and 71 respectively. When the relay V₃ has released, it cannot be again energized during the further setting up of the connection. It should, however, here be noted that as soon as the relay C₂ is energized, the relay U₂ is also energized as follows over its winding I: earth, contact 72_{c2}, winding I of relay U₂, contact 73_{hr}, driving magnet D₄ of the counting switch ZS₂, battery, earth. The magnet D₄ is not energized owing to the high resistance of winding I of relay U₂. The relay U₂ has therefore opened its contact 74_a and thereby prevents the magnet D_{3(ms2)} being connected up after relay V₃ releases.
 The transmission of the first impulse from the calling station and the opening of the contact 26_{a1} by the impulse receiving relay A₁, causes the removal of the short circuit around the winding I of relay V₂. Hence relay V₂ can operate and it opens its contacts 34_{v2} and 40_{v2} and closes the contact 74_{v2}. Battery is thereby connected over resistance 75 to the lead 41 of the trunk line VL₁ and the relay B₃ (Fig. 3) is thereby maintained energized over its winding II as follows:—
 earth, battery, resistance 75, contact 74_{v2}, 130

5 lead 41, contact 57_{c2}, normal contact 76 and wiper 77 of the switch ZS₂, junction point 78, contact 79_{t3}, lead 59, contact 65_{b3}, winding II of relay B₃, earth. The relay B₃ is also connected to the junction point 78 (Fig. 2). It is, however, of high resistance and is so much shunted by the winding II of relay B₃ (Fig. 3) that it cannot operate.

10 The first group selector I.GW₁ in known manner hunts for a free trunk line VL₂ and the connection is completed by the positioning of the other numerical switches (e. g. the II.GW₁ and LW₄ shown in Fig. 3).

15 It is assumed that the final selector LW₄ is provided with a side switch and that the impulse relays A₅ and B₅ are disconnected after the transmission of the trains of impulses for operating the driving magnets. It is also assumed that position 13 is the

20 speaking position of the side switch, into which it goes after the wanted subscriber T_{n5} has answered and in which position a feeding relay Y for the subscriber T_{n5} is connected up. In position 13 of the side switch, battery is connected to the lead 82 over a resistance 80 and the side switch contact 81, so that the relay B₂ in Fig. 2 is energized as follows: earth, battery, resistance 80, side switch contact 81 (position 13), lead 82, contact 83 and wiper 84 of the second group selector II.GW₁, contact 85_{p2}, contact 86 and wiper 87 of the first group selector I.GW₁, contact 88_{p1}, lead 59, contact 79_{t3}, junction point 78, relay B₂, earth. The

35 relay B₂ operates and causes the switch ZS₂ to move on to the next contact since the circuit for the driving magnet D_{4(zs2II)} is closed as follows:—earth, interrupter 89, contact 90_{b2}, off normal contact 91_{ks2II} of the switch 40 ZS₂, magnet D_{4(zs2II)}, battery earth. Hence the wiper 77 of ZS₂ is moved to the contact 92. The magnet D₄ cannot be again operated, since the contact 91_{ks2II} has now been opened.

45 The relay B₂ furthermore at its contact 93_{b2} connects earth to the relay A₂. In addition the relay S₁ is connected over contact 104_{b2} to the lead 54. The relay S₁ operates, opens its contact 53_{s1} and closes its contacts 99_{s1} and 112_{s1}. At the contact 112_{s1} the relay U₂ is maintained energized over its winding II.

50 To return now to the circuit changes, which take place in the calling sub-exchange UAI: it has already been described how the first train of impulses, which operated the first group selector I.GW₁, also moved on the digit switch MS₁ for instance to the contact 94. At the end of this train of impulses, the relay U₁ is energized as follows: earth, contacts 32_{v1}, 34_{v2}, wiper 35, contact 94, relay U₁ contacts 119_t and 120_{e1}, battery, earth. The relay U₁ connects itself in a holding circuit at its contact 121_{v1}; this circuit can, however, only be closed so long as local connecting devices LW₁ accessible 60 from the preselector II.VW₁ are free, since

only in this case is the contact 122_g closed. The second train of impulses for setting the second group selector II.GW₁ causes the driving magnet D_{2(ms1)} of the digit switch MS₁ to be operated in the same manner as 70 did the first train of impulses. Thereby the wiper 35 reaches for instance the contact 118. After the release of relay V₂ due to the prolonged short circuit of its winding I at contact 26_{a1}, the relay F is energized: 75 earth, contacts 32_{v1}, 34_{v2}, wiper 35, contact 118, windings I and II of relay F, battery, earth. The relay F closes its contact 95 and thereby connects itself in a holding circuit dependent on the contact 96_{v1} of the slow 80 releasing relay V₁. Furthermore the relay F opens the contact 67_t, so that the rotary magnet D_{2(ms1)} cannot be operated further by other trains of impulses.

85 If at the end of the conversation the wanted subscriber is the first to hang up, the side switch of the final selector LW₄ reaches the position 14. The circuit for the relay B₂ (Fig. 2) is however maintained, since in this position also the contact 81 (Fig. 3) is closed. When the calling subscriber T_{n1} (Fig. 1) also hangs up his receiver, the relay A₁ is permanently de-energized, hence the contact 26_{a1} remains open and the contact 27_{a1} remains closed. The winding II of relay C₁ is short circuited, and the relay C₁ therefore releases. Among other circuit changes, it opens its contacts 22 and 23_{e1}, and closes its contacts 97 and 98_{e1}. The circuit of winding I of the slow 90 acting relay V₁ is opened at contact 22_{e1}. At contact 97_{e1} however the following circuit is closed: earth, battery, winding II of relay V₁, contact 97_{e1}, lead 24, winding I of relay A₂, contact 93_{b2}, earth, so that the 95 relay V₁ remains energized in this circuit. The relay A₂ also operates and gives a metering impulse to the meter impulse repeating relay ZR at the repeater Ue of the exchange UAI over the following route: 100 earth, battery, contacts 99_{s1}, 100_{a2}, relay HR, contact 57_{c2}, lead 41, contacts 40_{v2}, 98_{e1}, relay ZR, contact 31_{v1}, earth. The relay ZR closes its contact 101_{z1} and thereby 105 connects the low resistance 102 in parallel with the high resistance 103 to the lead 17 coming from the second preselector II.VW₁. Thereby the current flowing over the meter Z at the first preselector I.VW₁ is increased to such an extent that the meter can operate 110 and the conversation can be metered. After the relay HR has been energized, the driving magnet D_{4(zs2II)} of the switch ZS₂ is energized as follows: earth, contacts 51_{a2}, 105_{hr}, magnet D_{4(zs2II)}, battery, earth. The relay HR at its contact 106_{hr} short circuits the relay A₂, hence it releases. The wiper 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 connected to the junction point 78 over the contact 58₂₂, wiper 62, the contacts 71 and 107 and the wiper 77. The relay B₂ releases and opens the contacts 93 and 104. The opening of contact 104₂₂ interrupts the holding circuit over the relays C₂, S₁ and C₃, and the first group selector I.GW₁ as well as the succeeding switches are released in known manner. When the contact 93₂₂ is opened, the relay V₁ at the repeater Ue is de-energized and releases.

The digit switches MS₁ and MS₂ as well as the counting switch ZS₂ are released in the following manner:

15 After the release of relay V₁ the relays V₂ and S are energized in the following route: earth, contact 33_{v1}, winding II of relay V₂, off normal contact 107_{kms1} of the digit switch MS₁, winding II of relay S, battery, earth. Both the relays S and V₂ operate and close their contacts 108_{v2} and 109_s. Thereby the following circuit is closed for the rotary magnet B_{2(ms1)}: earth, contacts 110_{v1}, 109_s, 108_{v2}, 67_t, 28_{a1}, 36, magnet D₂, battery, earth. The magnet D₂ operates, moves on the digit switch and at its contact 111_{d2} short circuits the relay V₂. The relay V₂ releases and opens its contact 108, whereby the magnet D₂ releases and 20 opens the contact 111. The relay V₂ now again operates and again closes the contact 108_{v2}. This cycle is repeated until the auxiliary digit switch reaches its normal position, wherein the off normal contact 107_{kms1} is opened. After the release of the rotary magnet D₂ it is impossible for the relay V₂ to again energize.

The relay U₂ in Fig. 2 was, as already mentioned, maintained energized during conversation over a contact 112 of relay S₁ and its winding II. Since the relay S₁ was de-energized after the release of relay B₂, the relay U₂ is also de-energized and closes the following circuit for the magnet D_{3(ms2)}: earth, battery, magnet, D₃, contact 46_{v3}, off normal contact 113_{kms2} of the digit switch MS₂, contact 74_{u2}, winding II of relay HR, earth. The magnet D₃ operates and closes the following circuit: earth, battery, winding II of relay U₂, contact 114_{d3}, winding III of relay HR, earth. The relay U₂ at contact 74_{u2} opens the circuit of the magnet D₃, whereupon the magnet releases and opens the circuit of the relay U₂. This cycle is repeated until the digit switch reaches its normal position, in which the contact 113_{kms2} is opened.

The switch ZS₂ is moved into its normal position at the same time as the digit switch MS₂, since the circuit of driving magnet D_{4(ms2)} is closed as follows: earth, battery, magnet D₄, off normal contact 115_{kzs2}, normal contact 116_{kzs1}, contact 117_{u2}, winding II of relay H_r, earth. The magnet D₄ also closes a contact 118_{d4} in the circuit of wind-

ing II of relay U₂, so that the moving on of the switch ZS₂ is dependent only on the operation of the magnet D₄ and the relay U₂. The driving circuit for the magnet D₄ is finally opened when the switch ZS₂ reaches its normal position since the contact 115_{kzs2} is then opened.

Consideration will now be given to the case when a connection is set up with a subscriber who is connected to an exchange located in a different traffic zone. Exchanges for which a zone payment has to be made are, for instance, reached over the eighth level of the first numerical switch. Hence the first group selector is set on the eighth level, in which it takes into use a free trunk line VL₅. The continuation of the trunk line VL₅ is indicated by VL₆ in Fig. 3. At the point (200, 201, 202) where these two lines meet, a trunk line VL₉ is connected coming from the bank contacts of those first numerical switches (I.GW₂) that are accessible to subscribers of the main exchange. Between the contacts 203, 204 and 205 at the last mentioned first numerical switch I.GW₂ and the meeting points 200, 201 and 202 are located the meter operating devices that are only operated for calls originated by the main exchange subscribers. These meter operating devices (MS₃, ZS1'/ZS2') are therefore not employed for the present connection. When the first group selector I.GW₁ is set on the eighth level, the digit switch MS₁ is at the same time set on to the eighth contact, which is for instance the contact 118. After the relay V₂ has released, the relay F is energized as before and prevents the rotary magnet D₂ being operated by further trains of impulses.

The wiper 45 of the digit switch MS₂ is likewise set on to the eighth contact, which in Fig. 2 is designated by 121. The winding III of relay HR is short circuited for the duration of the impulse train by the contact 47_{v3}. The relay HR is, however, energized upon the release of the relay V₃: earth, battery, resistance 46', wiper 45, contact 121, relay HR, winding III, earth. The relay HR operates and by opening the contact 73_{hr} interrupts the circuit over the winding I of relay U₂. The relay U₂ releases and closes the contact 74_{u2}, whereby the following circuit is closed for the magnet D₃: earth, battery, magnet D₃, contacts 46_{v3}, 113_{kms2}, 74_{u2}, relay HR, winding II, earth. The magnet D₃, by closing its contact 114_{d3}, energizes the relay U₂ over its winding II in series with the winding III of relay HR. The relay U₂ operates and opens the contact 74_{u2}, whereby the circuit for the magnet D₃ is opened, so that it de-energizes and opens the contact 114_{d3}. Thereupon the relay U₂ releases and closes contact 74_{u2}. This cycle is repeated until the wiper 45 reaches

the contact 122. This contact cannot be reached by the first train of impulses transmitted by the calling subscriber which will never exceed ten. As soon as the wiper 45 reaches the contact 122, the following circuit is established: earth, battery, resistance 46', wiper 45, contact 122, winding I of relay V_3 , lead 60, contact 123, wiper 62, contact 58₂₂, earth. The relay V_3 operates, opens the circuit for the automatic rotation of the digit switch MS_2 by opening the contact 46_{v3}, and at contact 48_{v3} connects the rotary magnet D_3 to the impulse contact 51_{a2}. The digit switch MS_2 has now been brought into a position in which it can be operated by the second train of impulses. The transmission of the second train of impulses causes the relay A_2 to be operated in the manner already described and the relay at its contact 51_{a2} sets the rotary magnet D_3 in operation. The circuit of the rotary magnet D_3 contains the winding II of relay V_3 , so that this relay remains energized for the duration of the train of impulses. The energization of the relay V_3 after the switch 45 has been set on the contact 122 also causes the relay HR to release, thus preventing the rotary magnet D_4 of the switch ZS_2 being operated by the relay A_2 .

Let it be assumed that the second train of impulses comprises only a single impulse and hence the wiper 62 of the digit switch MS_2 has been set on the contact 124, over which is connected up thereafter wiper 125 of the zone switch ZS_1 .

After the connection has been set up and the wanted subscriber has answered in the manner already described, the relay B_2 is energized and causes the switch ZS_2 to take one step as before; hence the wiper 77 of ZS_2 stands on contact 92. Furthermore the contacts 126 and 127 are closed in this position of ZS_2 . The relay S_1 has been again operated over the contact 104_{b2} in the manner already described and has connected up the relay U_2 over its winding II so that the contact 128_{u2} is opened and the contact 129_{u2} is closed.

The meter operating device has a time switch associated with it, which is moved on by the magnet D_5 at fixed intervals of time. After the contact 129_{u2} has been closed, the time switch is moved out of its normal position since the magnet D_5 is energized as follows: earth, interrupter 130, contacts 131_{b2}, 126_{zs2}, normal contact 132_{ze}, contact 129_{u2}, rotary magnet $D_5(zs)$, battery, earth. At the first step of the time switch ZE the contact 132_{ze} is opened and the contact 133_{ze} is closed.

It is assumed in the present example that the time switch has 36 contact positions and is moved on by a time contact 134_{nk}, which is closed every 5 seconds; it may for instance be operated by an electric clock. Hence one

rotation of the time switch corresponds to a duration of 3 minutes, which has been assumed to be a unit of time for the calls. The contact 134 is closed shortly before the time switch has completed a rotation. 70 Thereby the corresponding subscribers are given a buzzer tone, from which they recognize that a 3 minute period will be completed in a few seconds and that further charge will be made if the conversation is 75 continued. The circuit for repeating the signal, which is closed upon the closure of the contact, extends as follows: earth, secondary winding of the induction coil 135, contact 136_{ts}, wiper 137, contact 134_{ze}, winding II of relay B_2 , winding II of relay A_2 , earth. The buzzer tone is repeated from the windings II of the relays A_2 and B_2 to the windings I of these relays and can therefore be heard by the subscribers. When the time 85 switch upon its rotation reaches the last contact (the 36th) the driving magnet D_6 of the zone switch ZS_1 is energized as follows: earth, 135, contact 136_{ts}, wiper 137, contact 138_{ze}, magnet $D_6(zs)$, battery, earth. The 90 zone switch ZS_1 is moved on one step. The circuit changes just described are repeated at each rotation of the time switch ZE.

The zone switch ZS_1 , which is controlled by the time switch ZE, has its contacts connected with the contacts of the counting switch ZS_2 . The wiper 125 of ZS_1 is connected up for calls to the second traffic zone. The normal contact 139 is connected with the fourth contact 140 of the switch ZS_2 . 100 Since this switch is set on the first contact 92 as already mentioned, it has to take three steps before the wiper 77 reaches the contact 140. Hence for connections in the traffic zone II, three metering impulses have to be 105 transmitted for each conversation unit. When the zone switch ZS_1 has been advanced one step at the end of the first unit of time, the wiper 125 stands on the contact 141 which is connected with the seventh contact 110 142 of ZS_2 .

For calls to the traffic zone III the wiper 143 is connected up, as has been assumed in Fig. 2. The normal contact 144 upon which this wiper is standing, is connected to the 115 sixth contact 145 of ZS_2 . Hence for calls to the third traffic zone five impulses are transmitted for each time unit.

For calls to the fourth traffic zone, for which the wiper 146 of ZS_1 is connected up, 120 seven metering impulses have to be transmitted for each time unit, and for calls to the fifth traffic zone nine metering impulses have to be transmitted.

In the present system, devices are also 125 provided for limiting the duration of the different calls according to their value. This is achieved by means of the switch ZS_2 . In the present example this switch has 32 positions. The last five contacts 147 to 148 are 130

multiplied together and are connected with a relay T_3 . Since the zone switch ZS_1 is always moved on one step at the end of a three minute period, the wiper 125 of the zone switch ZS_1 reaches the ninth contact 149 at the expiration of 8 time units in the case of calls to the traffic zone II: the contact 149 is connected to the contact 147 of the switch ZS_2 . When the call has lasted so long, i. e. 24 minutes, the relay T_3 is energized in the following circuit: earth, contact 58_{c2}, wiper 62, contact 124, wiper 125, contact 149, lead 150, contact 147, relay T_3 , battery, earth. The relay T_3 operates, opens its contact 136 and connects the buzzer tone at its contact 151 to the windings II of the relays A_2 and B_2 . The calling subscriber therefore immediately receives the buzzer tone. In addition, however, the contacts 69 and 79_{t3} are also opened and the contact 152_{t3} is closed, hence the speaking connection is interrupted. However, the relay B_2 is maintained energized over the contact 152_{t3} and the resistance 68.

If a connection has been set up to the traffic zone V, then the wiper 62 of the digit switch MS_2 stands on the contacts 153, so that the wiper 154 is connected up. The normal contact 155 of this switch is connected with the tenth contact 156 of the switch ZS_2 . It is assumed that for a connection of such high value the maximum duration of a conversation is two units of time. The wiper 154 of the switch ZS_1 is at the end of the first time unit moved on to the contact 157, which is connected with the contact 158 of ZS_2 . At the end of the second time unit the driving magnet D_6 of ZS_1 again receives an impulse and the wiper 154 reaches the contact 159, which is connected with the contact 160 of ZS_2 . The relay T_3 is then at once energized and brings about the circuit changes already described.

When the calling subscriber hangs up his receiver at the end of a conversation in one of the traffic zones II to V the relay A_2 is energized as already described and transmits a metering impulse over the lead 41 to the meter repeating relay ZR in Fig. 1. Thereby the relay HR is again energized and by closing the contact 105 connects the driving magnet D_4 of ZS_2 to the impulse contact 51_{a2}. The relay HR at its contact 106_{hr} short circuits the relay A_2 , so that the relay A_2 slowly releases and opens the contact 51_{a2} in the circuit of the magnet D_4 and also the contact 100_{a2} in the circuit of relays HR and ZR .

The magnet D_4 releases and after a little while the slow acting relay HR also releases. Thereupon the relay A_2 again operates and causes the transmission of a second metering impulse and the moving on of the switch ZS_2 . This cycle is repeated until the wiper 77 reaches a contact, over which the relay B_2 is short circuited. If the zone switch ZS_1

was moved on three times during a conversation in the second traffic zone, the wiper 125 stands on the contact 161, which is connected with the contact 162 of the switch ZS_2 . When the wiper 77 reaches this contact, the relay B_2 is short circuited, since earth is connected to the wiper 77 over the contact 58_{c2}, wiper 62, contact 124, wiper 125, contacts 161 and 162. The relay B_2 releases, opens contacts 93 and 104_{b2}, whereby the relays C_2 and S_1 are permanently de-energized.

As soon as the transmission of metering impulses commenced the contact 127_{zs2} was opened, this contact being closed only in the first position of the switch ZS_2 , that is when the wiper 77 stands on the contact 92. Thus the operation of the time switch ZE is prevented during meter impulse transmission.

The switches MS_2 , ZS_1 and ZE are moved on into their normal position when the relay C_2 is de-energized after the release of relays B_2 and S_1 . The moving on of the time switch ZE is effected by the alternate operation of the driving magnet D_5 and the relay U_2 . The circuit of the driving magnet D_5 of the time switch ZE is closed over: earth, battery, magnet D_5 , contact 128_{u2}, off normal contact 170_{kze}, relay HR winding II, earth. The magnet D_5 closes its contact 171_{u2} and thereby energizes the relay U_2 , which opens the contact 128_{u2}, so that D_5 is de-energized. The relay U_2 is now de-energized and again closes its contact 128_{u2}, so that the magnet D_5 receives another impulse. The contact 170_{kze} is opened when the time switch ZE reaches its normal position. The circuit for driving magnet D_6 of the zone switch ZS_1 is closed over: earth, battery, magnet D_6 , contacts 172_{ks1}, 117_{u2}, winding II of relay HR , earth. The magnet D_6 energizes the relay U_2 over its contact 173_{u2}. The contact 172_{ks1} is opened when the zone switch ZS_1 reaches its normal position and the magnet D_6 cannot again be energized. The circuits for the magnets D_3 and D_4 , which move the digit switch MS_2 and the zone switch ZS_2 respectively into the normal position, have already been previously described.

The trunk line VL_1 cannot be taken into use so long as any of the switches MS_2 , ZS_1 or ZS_2 remain in the operated condition. This is due to the relay HR which at its contact 146 closes a circuit for the relay S at the repeater Ue (Fig. 1). As already mentioned, the relay S is energized over the off normal contact 107_{kms1} during the releasing motion of the digit switch MS_1 . When the digit switch MS_1 reaches its normal position, the contact 107_{kms1} is opened and the contact 175_{kms1} is closed. If at this time the relay HR in Fig. 3 is still energized, the relay S is maintained energized as follows: earth, resistance 176, contacts 146_{hr}, 42_{c2}, lead 41, contact 175_{kms1}, relay S , battery, earth. The relay S therefore maintains its contact 139.

18_s open, so that it is impossible for the trunk line VL₁ to be taken into use by a testing second preselector II.VW₁.

If a call is set up between the subscriber 3 T_{ns} of the main exchange HA, (Fig. 4) and a subscriber of an exchange accessible over the trunk line VL₆, the relays C₆, A₆ and B₆, are energized after the preselecting devices 10 I.VW₂ (Fig. 4) and II.VW₂ have been positioned. Thereafter in known manner the first numerical switch I.GW₂ is set on a level to which the trunk line VL₈ is connected. When such a free trunk line has been found, the following circuit is established: earth, 15 windings I and II of relay P_s, contact 206_{vs}, wiper 207, contacts 205 and 208_{vs}, relay C₇, lead 209 of the trunk line VL₉, junction point 202, lead 210 of the trunk line VL₆ to battery over switching devices of the 20 selectors in the distant exchange. The relay C₇ closes the contact 211_{c7} located in parallel with the contact 208_{vs} and energizes the relay V_s over the contact 212_{c7}, the contact 213 of the digit switch MS_s and the wiper 214. 25 Relay V_s opens the contact 208_{vs} and at contact 215_{vs} connects the relay A₇ to battery over the resistance 216. Between the trunk lines VL₈ and VL₉ lie the switching members of the meter operating devices, comprising 30 the switching devices MS_s, ZS₁' and ZS₂'. The method of operating these meter operating devices corresponds to that shown in Fig. 2, so that it is unnecessary to describe the circuit changes. The relay B₇ 35 corresponds to the relay B₃ and the relay T₄ corresponds to the relay T₃.

What I claim is:—

1. In a telephone system, calling and called lines, numerical automatic switches for establishing connections between said lines, other switches, means for transmitting impulses to said switches to cause them to perform switching operations during the process of setting up a connection, and means for then causing 40 said other switches to automatically move into a definite position from which they are again moved a distance dependent on the number of impulses in the subsequent train of impulses of the called number.

50 2. In an automatic telephone system, means including a plurality of automatic switches for bringing about the establishment of connections between calling and called lines, auxiliary switches associated 55 with said automatic switches, said automatic switches and said auxiliary switches responsive to each impulse of a plurality of trains of impulses, and means for causing said auxiliary switches to automatically move a definite distance between a plurality of impulse series.

60 3. In a telephone system, an automatic switch, another switch, means for transmitting impulses to said switches in accordance 65 with a digit of a called number, means for

then causing said other switch to automatically advance to a definite position, the first means being then effective to again move said switches in accordance with a second digit of a called number. 70

4. In a telephone system, a train of automatic switches responsive to series of impulses to establish talking connections between calling and called lines, another automatic switch responsive to the impulses of one series and non-responsive or responsive to the impulses of a succeeding series dependent on the number of impulses in the first series. 75

5. In a telephone system, an automatic switch, an auxiliary switch associated therewith means for transmitting impulses to said switches to cause the same to move a corresponding number of steps, means for then causing said auxiliary switch to automatically move to a definite position beyond any position attainable by a single impulse series, and means responsive to the definite positioning of said automatic switch to again render 80 said auxiliary switch operative responsive to a subsequent train of impulses. 85

6. In a telephone system, a calling line, automatic switches, an impulsive relay, means at the calling line for transmitting impulses to cause said relay to repeat impulses to operate one of said automatic switches to establish a connection and means for thereafter causing said impulsive relay to automatically transmit impulses to move another 90 of said automatic switches a distance dependent on the time lapse of the connection. 95

7. In a telephone system, automatic switches, means including an impulse repeating relay for transmitting a series of impulses to position said switches, one of said switches being positioned to extend a calling line towards a desired called line, another of said switches being positioned to determine the routing of the call, a third one of said switches being positioned to determine the 100 value of the connection in case a particular route is taken, a fourth automatic switch, and means automatically controlled by said impulse repeating relay, subsequent to the 105 positioning of said other switches, for causing the same to automatically operate said fourth switch a distance dependent on the position of one of said first switches. 110

8. In an automatic telephone system, a calling and called line, means including automatic switches for establishing a connection between said lines, auxiliary switches associated with said automatic switches, means controlled over said calling line for positioning said switches, and means dependent upon and subsequent to the operation of said first means for causing said auxiliary switches to automatically move a definite distance. 115

9. In a telephone system, a calling line, 120

automatic switches, an impulsing relay, auxiliary switches, means at the calling line for transmitting impulses to cause said relay to repeat impulses to operate said automatic switches and said auxiliary switches, and means for thereafter causing said impulsing relay to automatically transmit impulses to

move said auxiliary switches a distance dependent upon the time lapse of the connection.
